RAILROAD CROSSING TRAFFIC SYSTEM

Application filed June 14, 1927. Serial No. 198,825.

The present invention relates to a system of protecting railroads at grade crossings with other railroads.

Where railroad tracks cross each other at grade it is the custom of railroads to install a system of interlocking and signals to protect the trains on one line from being run into by trains on the other line. Such interlocking and signal systems are usually under the supervision and operation of a man stationed at or near the crossing, who, when a train approaches the crossing, sets the signals on the opposing line to stop trains on that line, and then clears the signals for the approaching train to proceed over the crossing. In the case of such plants, the signals are interlocked with each other so that only one route can be cleared at a time.

It is the purpose of this invention to provide a railroad crossing protection system effective in expediting and protecting trains operating over the crossing similarly to the system now ordinarily used by the railroads, but instead of having signalmen to operate the system the operation will be manually controlled from the train as it approaches the crossing.

Another object of the invention is to make the crossing protection system effective for trains operating at reduced speeds.

Still another object of the invention is the provision that a signal governing one route over the crossing can only be cleared when all signals governing on conflicting routes over the crossing are indicating "stop", and the tracks between signals are unoccupied.

Still another object of the invention is the provision of a system such that the first train operating the crossing protection system holds the right of way over the crossing.

Another object is to permit a train such as a freight to stop before the home signal governing it over the crossing and wait for another train such as a fast passenger train on a conflicting route to approach and operate the crossing protection system to let itself over the crossing.

A further object of the invention is to require a train to consume at least a certain predetermined time in approaching and pass-

ing over the track means in order that the crossing protection system may be operated.

A still further object of the invention is an arrangement of manual means on the train for the operation of the system such that it is only operative under prescribed speed conditions and automatically becomes inoperative as soon as the prescribed speed is exceeded.

A still further object of the invention is to make the engineer of the train alert to the dangers of the crossing by making it necessary for him to operate the protection system himself to let his train over the crossing.

Other objects of the invention will appear in the description and explanation which follows:

Figure 1 is a diagrammatic illustration of the invention showing the railroad tracks and crossing and the circuits on the roadside.

Figure 2 is a diagrammatic illustration of the circuits and equipment on the locomotive.

Figure 3 is a diagrammatic illustration of an alternative arrangement of one section of the roadside equipment and the circuits approaching the railroad crossing.

Figure 4 is a diagrammatic illustration of the circuits and equipment on the locomotive in a different form from that shown in Figure 2, and this may be considered as the preferred form.

Figure 5 is an enlarged view showing the connections at the rail crossings in Figure 1.

The invention consists generally of co-operating means on the roadside and on the train constituting a complete signal system. The means on the train is manually operated while the roadside means is automatically responsive to the train means. The combination is so constituted that any train, which secures the right of way over the crossing, is in effect the signal operating station upon entering its right of way, and after such entry the system is automatically operable to maintain itself set against other trains, and after the train has safely passed the crossing and has passed the confines of the system, there is automatic operation to establish the initial condition.

The means on both the train and the track

by which a co-operative relation is obtained are preferably such that physical contact or mechanical operation is dispensed with. Specifically, electrical induction is the preferred co-operative force. Consequently the embodiment of the invention hereinafter described is directed to a system in which electro-magnetic inductors are used.

Fig. 2 represents a simple train inductor system as provided on a locomotive. This system comprises generally in one circuit 10, an electro-magnetic inductor 11, an electric generator 12, a hand switch 13, which may be of the impulse type, or of the time interval type which automatically opens after a predetermined time, and if desired a speed governed switch 14 operated by a governor 15. The governor is connected with the running gear so that the circuit is automatically closed 20 at the switch 14 when a predetermined condition of speed obtains. The line 10^a represents a modification of the circuit to cut out the speed governed switch, if desired. It is to be understood that energizing this system by 25 the engineer, so affects the track means as to operate the track signals of this invention.

Fig. 4 represents a modified and a preferred form of system for the locomotive. This corresponds to the system of Fig. 2 insofar as it has connected in series an inductor 16, a speed controlled switch 17 and a generator 18. The hand switch of Fig. 2 is herein replaced by a relay switch associated with a suitable speed indicating signal and 35 a manual operating means. There is a relay coil 19, one side of which is connected directly to the inductor 16 by wire 20. The other side is connected to the generator through contact 21 and relay switch 20, which is operated by the coil 19 and manual operating means 24. Inductor 16 is connected on the other side to generator 18 by a conductor leading through the speed controller switch 17. 21 is a front contact for the relay, there being also a back contact 22 connected through a lamp signal 23 across the generator but through the speed switch 17. A push button 24 is associated with the armature to move it from its normal position 40 against contact 22 toward contact 21. When speed switch 17 is closed, i. e., under a predetermined speed, the indicator signal 23 shows this fact. If the signal is extinguished, the speed is greater than that which may be 45 prescribed for operating the system. Pushing the button shifts the current flow, by bringing switch 20 against contact 21, thus energizing the inductor and the relay coil. 50 The relay maintains this condition until the circuit is again broken, as by the speed controlled switch upon exceeding the prescribed speed limit. The button 24, being of the impulse type, cannot be held or fastened in the 55 up position to keep armature switch 20 per-

manently against contact 21 whether coil 19 is energized or not.

The track system in connection with which the present invention is herein described, is a grade crossing at which one line A—B (Fig. 1) crosses another line C—D, the two rails of each being represented by the heavy lines. At the junction the rails are insulated and suitable electrical connections *a*, *b*, *c* and *d* are used to complete the rail circuits. At 70 predetermined distances, say 500 feet, along each direction from the junction, home signals 25A, 25B, 25C and 25D are positioned. The stretches of track A—B and C—D between home signals are insulated lengths and each is provided with a track circuit. For A—B the track circuit battery is 26A and the track circuit relay is 29A. For C—D the battery is 26D and the relay is 29C. The coil 56C of relay 29A is connected to the track rails A—B by conductors 27A and 28B. The coil 56A of relay 29C is connected to the track rails C—D by conductors 27C and 28D. For the purpose of explanation these relays are to be considered as part of an "interlocking system" later to be described. The function of such an interlocking system is to co-ordinate the signals and the actions along all directions from the junction, the action in each direction being the same as that for any other direction. Each of the four lines A, B, C and D, out from the junction, are similarly equipped and similarly wired, providing three conductor leads from the equipment at the home signal to the interlocking system. For this reason it is sufficient to describe the equipment and the wiring at one of the signal stations and then to describe the co-ordination of the four similar track systems as they are related in the interlocking system.

The track system in the direction A, will serve this purpose. Between the rails, outside of the insulated length of track, there is an inductor 30 influenced by the locomotive inductor. The track inductor is connected in circuit 31 with the coil 32 of a suitable so-called inductor relay 33. The inductor relay switch 34 is connected into a circuit, which is completed through the interlocking system, and which includes wires 35 and 36 leading thereto. The purpose of the track inductor is to close the circuit between wires 35 and 36 at the track system end, but it is to be understood that as soon as the train inductor has completed its movement over the track inductor, the relay switch 34 will open. Consequently means are employed to maintain the circuit closed after the train has passed. This is accomplished by a second relay 37 having the coil 38 interposed in the line of the circuit wire 36 leading to switch 34. The armature of 38 provides a relay switch 39 which is in parallel with relay switch 34 and which is closed on energiza-

tion of coil 38, this switch being connected by wire 40 to the conductor connecting relay switch 34 with the coil 38 and by wire 41 to the wire 35. Thus, when the inductor relay switch 34 opens, the coil 38 remains energized if there is current flowing in circuit wires 35-36. Relay 37 is also employed as the home-signal controlling means. There is a second armature 42 associated with the 10 coil 38 which serves as a switch arm between a front contact 43 and a back contact 44. This switch 42-43 controls the home signal by a circuit including a source of electricity 45, wire 46, switch 42-43, wire 47, home-signal 25A, wire 48 and source 45. The 15 home-signal is arranged to indicate "clear" or "proceed" when current flows in the last described circuit.

When no current flows through the home-signal it automatically indicates "stop" and in this condition it is arranged to affect the electrical circuits by closure of a control switch 49 associated with the signal. Thus, switch 49 is under control of the relay 37 when the signal 25A is controlled. Switch 49 is connected by wire 50 to the back contact 44 of the relay 37 and the wire 46 to battery 45, and by wire 51 to the interlocking system. A wire 52 connects lines 36 and 48. It is to be noted that switches 49 and 42-44 are in series and operate together. Switch 49 could be omitted, but it serves as a check on the position of a semaphore arm when used.

The foregoing describes the circuit arrangement and equipment at the location of signal 25A. The arrangement of the equipment and circuits at each of the other signals 25B, 25C and 25D is the same as that here described for 25A. At the signal 25A the conductors 51, 36 and 35 connect respectively with the conductors 51A, 36A and 35A leading to the interlocking system. From the signal location 25B the conductors 51B, 36B and 35B lead to the interlocking system. Similarly three conductors correspondingly numbered but with the suffixes C and D lead respectively from signals 25C and 25D to the interlocking system.

The interlocking system is represented in Fig. 1 within the boundary designated by dotted line 55. It includes the track relays 29A and 29C already described. The track relays comprise the coils 56A and 56C and the switches 57A and 57C respectively. For each of the track systems along the directions A, B, C and D there is a repeater relay designated 58A, 58B, 58C and 58D, the coils of which are respectively connected to the wires 51 and 36 of the separate track systems. However, all the four wires 36 are connected in common to provide a so-called common return. The switches of the repeater relays 58 are not identical. Relay 58A has three

switches A1, A2, and A3. Relay 58B has a

single switch B1. Relay 58C has three switches C1, C2, and C3. Relay switch 58D has two switches D1 and D2. A source of electricity is provided for the signal control relay coils 38 and for the interlocking system. These various elements are connected as follows:

One side of the source 59 is connected by wire 60 to the common return 36 of the repeater relay coils. The other side of the source is connected by line 61 through the track relay switches 57C and 57A to the junction point 62. At 62 the line splits, one part leading to one side of switch B1, and the other side leading to one side of switch D2. The other side of switch B1 is connected by wire 63 to one side of switch D1, thence by the parallel wires 64 and 65 to switches A1 and C1 respectively.

The other side of switch C1 is connected to the wire 35A from the track system along A. The similar wires 35B, 35C, and 35D are connected respectively (as the only connections) to switches A3, A1 and A2. The other sides of switches A2 and A3 are connected by wires 66 and 67 to switches C2 and C3 respectively. From switch C2 the line runs by wire 68 to wire 63; and from switch C3 it runs by wire 69 to switch D2 through which it connects with the junction 62 already described.

For the purpose of illustrating the operation of the system it will be assumed that a train approaches the crossing from direction A. The normal status of the system is such that every home signal 25 is set at "stop". The inductor relay switches 34 are open and also the signal control switches of relays 37. The signal operated control switch 49 and switch 42-44 are closed, thus completing a circuit through the track system between wires 36 and 51, as follows: wire 36, wire 52, battery 45, wire 46, armature 42, back contact 44, control switch 49, wire 51. Wire 51 connects to wire 51A; and since wires 36 and 51A connect to coil 58A, this latter is energized with control switch 49 and contact 42-44 closed. Thus the switches A1, A2 and A3 are closed normally. In the interlocking system a similar energized circuit is continued through each of the repeater relay coils 58 leading to each signal location and similarly controlled for each track system. The energizing of these coils, therefore, normally holds the various switches of the repeater relays closed as shown in the drawings; i. e., 58B energized holds switch B1 closed; 58C energized holds switches C1, C2 and C3 closed; and 58D energized holds switches D1 and D2 closed.

When an approaching train attempts to enter the protected region of the crossing the engineer energizes the train inductor, in the manner above described, and if the tracks A-B and C-D between the signals are clear such operation will shift the home signal

corresponding with the inductor energized from "stop" to "clear". This shifting operation is effected by the momentarily induced current in track inductor 30, thus closing relay switch 34, which completes the circuit comprising, conductors 35 and 35A, switch C1, conductor 65, switch D1, conductor 63, switch B1, conductor 61, switch 57C, switch 57A, conductor 61, battery 59, wire 60, common conductor 36, relay coil 38, and conductor leading to front contact of switch 34. The closure of this described circuit energizes coil 38 of relay 37 closing switch 39, and shifting switch 42 from back contact 44 to front contact 43. With the closing of stick switch 39, coil 38 remains energized in a circuit comprising battery 59, wire 60, common conductor 36, coil 38, conductor 40, switch 39, conductors 41 and 35A, switch C1, conductor 65, switch D1, conductor 63, switch B1, conductor 61, switches 57C and 57A and conductor 61 to the other terminal of battery 59.

When switch 42 is shifted from back contact 44, relay coil 58A is deenergized and switches A1, A2 and A3 controlled by 58A are opened, thus opening the controlling circuits respectively of the relays corresponding to 38 and associated with signals 25C, 25D and 25B. Under these conditions, a train approaching the crossing from directions C, D, or B can not clear the signal giving it the right of way over the crossing even though it should energize the inductor in its track in an attempt to do so.

35 The shifting of switch 42 to the front contact 43 closes a circuit from battery 45 and conductor 46 through conductor 47, signal mechanism 25A and conductor 48 to battery 45, thus clearing the signal 25A so that the approaching train now has the right of way over the crossing.

Accepting the clear signal 25A, the train proceeds in the track A-B and while therein the wheels and axles connect across the track rails shunting and deenergizing the relay 29A so that contact 57C is opened. The opening of contact 57C deenergizes the relay coil 38 so that switch 39 is opened causing signal 25A to resume the stop indication. Also, 50 since open contact 57C holds open the controlling circuits for all the signals, no other train on any route can clear a signal to pass over the crossing. When the train passes out of the stretch A-B, track relay 29A is again energized closing the contact 57C, and the interlocking is again in normal condition to be operated by a following train coming from direction A, or by a train approaching the crossing on any of the other routes.

55 60 The operation in the case of a train approaching from directions B, C or D is similar to that explained for the train approaching the crossing from direction A.

In the case of a train approaching from direction C and clearing signal 25 C, relay

coil 58C is deenergized opening contacts C1, C2 and C3, thus holding signals 25A, 25D and 25B at stop. For trains approaching from directions B or D relay coils 58B or 58D are deenergized respectively thus blocking all the conflicting routes.

With a train in the stretch C-D track relay coil 56A is deenergized to hold the signals of all routes at stop.

A modification of the track inductor circuit is shown in Fig. 3, which may be considered as employed in combination with the first described and modified train inductor means of Fig. 2, with conductor 10A substituted for the circuit through the speed controlled switch 14. In the train circuit for this combination the time interval switch 13 of Figure 2 is preferably employed without the speed controlled switch, the energized circuit being, generator 12, conductor, switch 13, conductor, inductor 11 and conductors 10 and 10A. The modification in the track includes a time relay switch interposed between the track inductor and the inductor operated relay. In Fig. 3 the track inductor 70 is in circuit with the usual relay 71 (corresponding to relay 33) through a relay switch 72 controlled by coil 73, these two latter elements constituting a time relay J in which a predetermined interval of time elapses after energization of 73 before the switch 72 is closed. Coil 73 is in series with a battery 74, and a relay switch 75, held open by an energized track relay 76 connected by an insulated section S of the track lying between the signal and the approaching train and in the region including the track inductor. A track battery 27 provides current for the track relay 76.

In the operation, as soon as a train enters the track section S, relay 76 is de-energized closing the time interval relay circuit. The engineer closes the particular switch 13 in the locomotive. The track inductor is placed between the entrance and exit of track section S and the speed of the train must be so regulated that the inductors co-operate after the track inductor circuit is closed. If the speed of the train is too fast the track inductor will be passed before time relay J closes the circuit of the track inductor relay 71. If the speed of the train is too slow the locomotive switch 13, if of the time interval type, will open before the track inductor has been reached, requiring the special attention of the engineer to again close the train-carried circuit if he wishes to open the right of way to his train. The timed relations of the switches may be varied to meet required conditions.

The invention therefore provides an interlocked railway grade crossing system of such character that the engineman of a train, desiring to cross over the railway crossing, may operate from the moving train the safety devices commonly provided, under the control

of an attendant on the ground, to protect trains in the use of the crossing. Novel features of the invention also include the provision for obtaining the right of way on but one route in one direction at one time of several intersecting routes, and means for restricting the speed at which trains will enter the interlocking limits of the crossing.

The present invention is not to be considered as limited to the specific disclosure and it is to be understood that it is applicable to any plurality of intersecting crossings by the interlocking of similar independent track systems. The invention in its broadest aspect 10 contemplates all the arrangements, modifications and embodiments falling within the scope of the appended claims.

What I claim as new is:

1. In a railroad crossing protection system of the character described including an interlocking means for coordinating electrical circuits, a track system comprising means along the track adapted to receive an impulse from a passing train, a home signal located between said means and the rail junction normally indicating "stop" and adapted to be changed to indicate "clear", a local electric circuit adapted upon closure to change the signal to "clear", said circuit comprising an electrical source, a relay operated switch, and said signal; a relay coil for said switch, a current providing means adapted to energize said coil upon the receipt of said impulse from the train, a second relay switch 25 associated with said coil, normally live terminals connected into the interlocking means, a loop of a circuit connected to said terminals comprising said second relay switch, and said relay coil, whereby when 30 said terminals are alive the signal may be held "clear", and when said terminals are dead the signal indicates "stop", and a loop of a circuit normally completed in the interlocking means, said loop comprising in 35 series, a switch adapted to be closed when the signal indicates "stop", and the electrical source.

2. In a railroad crossing protection system of the character described including an interlocking means for co-ordinating electrical circuits, a track system comprising a signal normally indicating "stop", an impulse receiving member adapted to be conditionally influenced by a passing train, means 50 responsive to the receipt of an impulse to change the signal to indicate "clear" during the continuation of said impulse, electric terminals connected to the interlocking means, means in circuit with said terminals 55 to maintain the signal at "clear" when said terminals are alive and in the absence of an impulse to permit when said terminals are dead the return of the signal to normal "stop" position, and a loop of a circuit normally completed in the interlocking system

comprising in series, a source of electricity and a switch adapted to be closed when the signal is in "stop" position.

3. In a railroad crossing protection system of the character described including an interlocking means for coordinating electrical circuits, a track system comprising a signal normally indicating "stop", a track-side inductor adapted to be influenced by an inductor on a passing train, a relay connected in a closed circuit with said track side inductor, a control relay having a coil included in a circuit comprising the switch of the inductor operated relay, said coil, and a pair of normally live terminals connected into the interlocking means, two switches forming part of the control relay, one being connected in parallel across the inductor relay switch to continue energization of the control relay coil initiated by the inductor relay when said pair of terminals are alive, the other switch of the control relay being adapted upon energizing the control relay to shift the signal from "stop" to "clear", a means associated with said switch and signal to operate the signal, and a loop of a second circuit normally completed in the interlocking means, comprising in series, a source of electrical energy and a switch adapted to be closed at the "stop" signal and open at the "clear" signal.

4. In a railroad crossing protection system having a means for interlocking a plurality of similar track systems, a track system comprising in combination, a home signal normally indicating "stop", means along the track adapted for conditional operation from a train approaching said signal to change the signal from "stop" to "clear", a pair of normally live terminals controlled from the interlocking means, a circuit loop connected to said terminals including means adapted to permit such a change of the signal from "stop" to "clear" when said terminals are alive and to prevent such change when said terminals are dead, another pair of normally live terminals leading to the interlocking means, and means associated with said train operated means adapted to render said last mentioned terminals dead upon a "clear" indication and alive upon a "stop" indication.

5. In a railroad crossing protection system having a means for interlocking a plurality of similar track systems, a track system comprising in combination a home signal normally indicating "stop", means along the track adapted for conditional operation from a train approaching said signal to change the signal from "stop" to "clear", said signal when cleared, being maintained in the clear position by means independent of any influencing action of said train until said signal is passed by the train, loops of two control circuits extending between the interlocking means and the track system, one circuit being

enlivened and controlled from the interlocking means, and the other being enlivened and controlled in the track system, means in the loop of the first circuit adapted to permit train operation of the signal when said circuit is alive, and means in the loop of the second circuit associated with the signal in such a way as to render the circuit dead when the signal indicates "clear".

10 6. A railroad crossing protection system comprising in combination, a plurality of track systems including a signal and means adapted conditionally to change the signal from normal "stop" indication to "clear" in response to a condition initiated on a passing train approaching said signal, an interlocking means including a plurality of relays, each relay being located in a normally closed relay circuit extending between the interlocking means and each track system, means adapted to open each relay circuit upon a change in the corresponding signal from "stop" to "clear", a conditioning circuit extending between each track system and the interlocking means adapted to be enlivened in the interlocking means and normally closed therein, means in the track system to close said circuit by operation from the train, means in the track system responsive to current flow resulting from said closure to permit changing the signal from "stop" to "clear" and thereafter to maintain said signal "clear" till the train has passed the signal, and means in the interlocking means adapted during a "clear" signal to prevent a controlling current flow to any other track system.

7. A railroad crossing protection system comprising in combination, a plurality of track systems including a signal and means adapted conditionally to change the signal from normal "stop" indication to "clear" in response to a condition initiated on a passing train approaching said signal, an interlocking means including a plurality of relays, each relay being located in a normally closed relay circuit extending between the interlocking means and each track system, means adapted to open each relay circuit upon a change in the corresponding signal from "stop" to "clear", a conditioning circuit extending between each track system and the interlocking means adapted to be enlivened in the interlocking means and normally closed therein, means in the track system to close said circuit by operation from the train, means in the track system responsive to current flow resulting from said closure to permit changing the signal from "stop" to "clear" and thereafter to maintain said signal "clear" till the train has passed the signal, means in the interlocking means adapted during a "clear" signal to prevent a controlling current flow to any other track system, and means associated with the track sections and the interlocking means adapted

to break all of said conditioning circuits when a train is in a section.

8. A protection system for grade crossing railroads comprising in combination, a signal and a signal operating system located on each rail line remotely from the crossing to govern a train approaching the crossing, said system being adapted for conditional operation from the train, a signal controlled interlocking station for controlling the operation of each signal, said station including electrical control means extending therefrom and controlled therein to each system to both permit and prevent local signal operation, and a second electrical controlling means extending from each system to the interlocking station arranged to cause all but one of the first electrical controlling means to prevent signal operation when the signal of that one indicates a right of way over the crossing.

9. A protection system for grade crossing railroads comprising in combination, a signal and a signal operating system located on each rail line remotely from the crossing to govern a train approaching the crossing, said system being adapted for conditional operation from the train, a signal controlled interlocking station for controlling the operation of each signal, said station including electrical control means extending therefrom and controlled therein to each system to both permit and prevent local signal operation, a second electrical controlling means extending from each system to the interlocking station arranged to cause all but one of the first electrical controlling means to prevent signal operation when the signal of that one indicates a right of way over the crossing, and means associated with the track sections between the signals for operation by a train on the tracks to render all the first mentioned controlling means ineffective to permit a signal operation to indicate "clear".

10. In a railroad crossing protection system, time governed means on the train in co-operation with time interval governed trackside means for clearing the route over the crossing.

11. In a railroad crossing protection system, means on the train, responsive to the speed of the train, co-operating through an air gap with roadside means to clear the route over the crossing.

12. In a system for producing track-side operation from a train in combination, operating means on the train comprising electrically energized means for effecting a track-side operation, a source of electrical energy, and a manually operated switch capable of automatic release after a predetermined time interval following switch closure, and track-side means comprising devices responsive to said operating means through an air gap.

13. In combination, means on a train adapted to be electrically energized for a

predetermined time interval, track-side means actuated by the energized train means, controlling means conditionally responsive to said actuated track-side means, and other means adapted to be operated by the train in moving over a given length of track in a given time interval to permit response of the controlling means to the actuated track-side means.

14. A time interval train controlled track signal system having in combination a track signal conditionally responsive for actuation, a track-side inductor arranged to be energized from a train, a relay for operating the conditionally responsive signal and a time delayed switch in series with said inductor, an independent relay circuit having a switch arranged upon closure to effect closure of the delayed switch, an insulated section of the railway track within which the inductor is placed a predetermined distance from one end, a battery and a relay across the rails of the track section, said relay being associated with the switch in the independent circuit in such a manner that said circuit is closed when the track relay is deenergized by the passage of a train over the rails, the delayed action of the time switch and the location of the inductor being such as to require less than a predetermined train speed for operation of the signal from the train.

15. In combination, an electric controlling device on a train adapted to be manually set for a predetermined interval of activity, a track-side means adapted to be responsive to said device during its period of activity upon coincidence, means associated with the track adapted automatically upon the train passing a given point located at a predetermined distance from the track-side means to initiate a timed and delayed action in said track-side means leading to its responsive condition, the manual operation of said switch being made in given relation to the train passage at the given point, the distance between said point and said track-side means, and the time of activity of the train device all being such as to require less than a given train speed or further manual attention to effect co-operation of the train device and the track-side means.

16. In combination, two intersecting insulated lengths of railroad track mutually insulated from each other, a battery and relay for each length arranged for short circuiting the relay when a train is within any length, train signal systems adapted to be conditionally operated by a train for each end of each length to govern the entry of a train into said length, and interlocking means associating all the signal systems and the track relays into a co-operative whole, whereby operation of one signal to "clear" any length renders the other signals inoperative, and the presence of a train within any length renders

a signal inoperative to "clear" any other track.

17. In combination, intersecting insulated lengths of railroad track mutually insulated from each other, an electrical circuit for each length arranged to be influenced by the presence of a train in the length, train signal systems adapted to be conditionally operated by a device on a train for each end of each length to govern the entry of a train into said length, and interlocking means associating the signal systems and the electric circuits into a cooperative whole, whereby operation of one signal to "clear" any length renders the other signals inoperative, and the presence of a train within any any length renders a signal inoperative to "clear" any other track.

18. In combination, intersecting lengths of railroad track mutually insulated from each other, an electrical circuit for each length arranged to be influenced by the presence of a train in the length, a signal for each length adapted for conditional operation from train carried devices in cooperation with track side devices, track side devices holding said signal at "clear" after same has been "cleared" for the entry of a train into said length, and interlocking means associating the signals, track side devices and electric circuits into a cooperative whole, whereby operation of one signal to "clear" for any length renders the other signals in-operative to "clear", and the presence of a train within any length renders all signals inoperative to "clear".

19. In combination, intersecting lengths of railroad track, an electric circuit for each length arranged to be influenced by the presence of a train in the length, a signal adapted to be operated from a manually controlled speed governed train carried system cooperating with a track system for each length of track to govern the entry of a train into said length, and interlocking means associating the signals, track systems and electric circuits into a cooperative whole, whereby the operation of one signal to "clear" for any length renders the other signals inoperative to "clear", and the presence of a train within any length renders all signals inoperative to "clear".

20. In a crossing protection system in combination, intersecting lengths of track the entry of a train to each of which is governed by a signal, train means for conditionally actuating a track-side means, controlling means responsive to said track side means when actuated for operating a signal, and other means adapted to be operated by the train in approaching a length of track to permit response of the controlling means to the actuated track means for operating the signal for said length.

21. In a crossing protection system in combination, intersecting lengths of track the entry of a train to each of which is gov-

erned by a signal, means interlocking the operation of said signals such that when one signal indicates "clear" the other signals must indicate "stop", train carried means for optionally actuating a trackside means, controlling means responsive to said trackside means when actuated for operating a signal to "clear", and other means adapted to be operated by the train in approaching a length 5 of track to permit response of the controlling means to the actuated track means for "clearing" the signal for said length.

22. In a crossing protection system in combination, intersecting lengths of track the entry of a train to which is governed by a signal, train carried means for actuating a trackside means, controlling means conditionally responsive to said actuated trackside means for operating a signal, and other 15 means adapted to be operated by the train in moving over a given length of track in a given time interval to permit response of the controlling means to the actuated trackside means for operating the signal for said 20 length.

23. In a crossing protection system in combination intersecting lengths of track the entry of a train to each of which is governed by a signal, train carried means adapted to 25 be set for a predetermined interval of activity for actuating a trackside means on coincidence, controlling means responsive to said actuated trackside means for operating a signal for one of said lengths, and other 30 means associated with said controlling means for holding said signal in the condition to 35 which operated.

24. In a crossing protection system in combination intersecting lengths of track the entry of a train to each of which is governed by a signal, train carried means adapted to 40 be set for a predetermined interval of activity for actuating a trackside means on coincidence, controlling means responsive to 45 said actuated trackside means for operating a signal for one of said lengths, and other means associated with said controlling means for holding said signal in the condition to 50 which operated independent of any influencing action of said train till the signal is passed by the train.

25. In a crossing protection system in combination, intersecting lengths of track the entry of a train to each of which is governed by 55 a "clear" signal, train carried means adapted to be set for a predetermined interval of activity for actuating a trackside means on coincidence, controlling means responsive to said actuated trackside means for "clearing" 60 a signal for the length of track the train is to enter, and other means associated with said controlling means for holding said signal at "clear" after same has been "cleared."

26. In a crossing protection system in combination, intersecting lengths of track the

entry of a train to each of which is governed by a "clear" signal, means interlocking the operation of said signals such that when one signal is "cleared" the other signals must indicate "stop," train carried means adapted 70 to be set for a predetermined interval of activity for actuating a trackside means on coincidence, controlling means responsive to said actuated trackside means for "clearing" a signal for one of said lengths, and other 75 means associated with said controlling means for holding said signal in the "clear" condition after same has been "cleared."

27. In a crossing protection system in combination, intersecting lengths of track the entry of a train to each of which is governed by a "clear" signal, train means for actuating a trackside means, effective only under a restriction in the speed of the train, controlling means responsive to said actuated trackside 80 means for "clearing" a signal for the length of track the train is to enter, and other means associated with said controlling means for holding said signal "clear" after same has 85 been "cleared."

28. In a crossing protection system in combination, intersecting lengths of track the entry of a train to each of which is governed by a "clear" signal, means interlocking the operation of said signals such that when one 90 signal indicates "clear" the other signals must indicate "stop," means on a train for actuating a trackside means on coincidence effective only under a prescribed rate of speed for the train, controlling means responsive to said actuated trackside means for "clearing" a signal for the length of track the train is to enter and other means associated with said controlling means for holding said signal "clear" after same has 95 been "cleared."

29. In a crossing protection system in combination, intersecting lengths of track, track circuits for said lengths, signals controlling the entry of trains into each length, a circuit for each route corresponding with each signal containing a repeating relay which is energized when the signal for said route indicates "stop," a controlling relay for each signal which may be energized to "clear" said signal when the repeating relays for routes 100 conflicting with said route are energized and said track circuits are not occupied, a controlling device on a train adapted to be made active, a trackside means adapted to be responsive to said active controlling device to energize the controlling relay to "clear" said signal, and means responsive to said controlling relay to hold said signal "clear" after 105 same has been "cleared."

30. In a crossing protection system in combination, intersecting lengths of track, a track circuit for each length, signals governing the entry of trains into each length, a circuit for each route corresponding with each signal containing a repeating relay which is energized 110

gized when the signal for said route indicates "stop," a controlling relay for each signal which may be energized to "clear" said signal when the repeating relays for routes conflicting with said route are energized and said track circuits are not occupied, a controlling device on a train adapted to be made active, and a track side means adapted to be responsive to said active controlling device to cause the controlling relay to "clear" said signal and hold same "clear."

31. The combination with the intersection of a plurality of railroad routes of protective devices on each route controlling train movements over said intersection, track circuits for said intersecting routes, instrumentalities for operating said devices, train carried means in cooperation with track side means controlling said instrumentalities to optionally "clear" a route for a train to pass over the intersection and hold said route "clear," and means operated by said track circuits restoring the instrumentalities to normal condition when the train has passed over the intersection.

32. The combination with the intersection of two or more railroad routes of protective devices on each route normally prohibiting train movements over said intersection, track circuits for said intersecting routes, instrumentalities for operating said devices, train carried means in cooperation with trackside means controlling said instrumentalities to optionally "clear" a route in one direction for a train to pass over said intersection, and means operated by said track circuits restoring said route to normal condition after the train has passed the intersection.

33. In a crossing protection system in combination, intersecting lengths of track the entry of a train to each of which is governed by a signal, train carried means adapted to be operated for actuating a trackside means on coincidence, and controlling means responsive to said actuated trackside means for operating a signal for one of said lengths and for maintaining said signal in the operated condition independent of any shunting action of said train till the signal is passed by the train.

34. In a railway crossing protection system in combination, intersecting lengths of track, a signal for each length governing train movements over the intersection, trackside means along each length, means on a train adapted to be operated to actuate one of said trackside means, controlling means responsive to such actuation to "clear" one of said signals for the train to proceed over the intersection and means associated with said one signal operative while said signal is at "clear" to render the signals on the other lengths inoperative to "clear".

35. In a railway crossing protection sys-

tem in combination, intersecting lengths of track, the entry of a train to each of which is governed by a signal, train carried means adapted to actuate a trackside means, said trackside means being actuated only when the speed of the train is under a prescribed rate, controlling means responsive to said actuation to operate one of said signals for the train to proceed over the intersection and means associated with said one signal operative while said signal is at "proceed" to render the signals on the other lengths inoperative.

36. In a railway crossing protection system in combination, intersecting lengths of track, the entry of a train to each of which is governed by a signal, train carried means adapted to be set for a predetermined interval of activity for actuating a trackside means on coincidence, controlling means responsive to said actuated trackside means for "clearing" a signal for one of said lengths, and means associated with said one length operative by the presence of the train in said length to set said signal at "stop".

37. In a railway crossing protection system in combination, intersecting lengths of track, the entry of a train to each of which is governed by a signal, train carried means adapted to actuate a trackside means on coincidence, said trackside means being actuated only when the speed of the train is under a prescribed rate, controlling means responsive to said actuated trackside means for operating a signal for one of said lengths, and other means associated with said controlling means for holding said signal in the condition to which operated.

In testimony whereof, I have subscribed my name.

ARCHIBALD G. SHAVER.
